UNITED STATES PATENT OFFICE.

THOMAS B. ATTERBURY, OF PITTSBURG, PENNSYLVANIA.

DESIGN FOR A BOTTLE OR JAR.

SPECIFICATION forming part of Design No. 18,219, dated April 3, 1888.

Application filed February 27, 1888. Serial No. 265,516. Term of patent 7 years.

To all whom it may concern: •

Be it known that I, THOMAS B. ATTERBURY, a citizen of the United States, residing at Pittsburgh, in the county of Allegheny and State of Pennsylvania, have invented and produced a new and original Design for Bottles or Jars; and I do declare the following to be a full, clear, and exact description of the same, reference being had to the accompanying drawings, forming a part thereof.

My invention relates to designs for glass bottles or jars for mustard and like substances; and it consists of an oval or flat body having an annular rim or projection near the top and having the sides at the ends of the ovals fluted.

My invention consists, further, of an ornamental cap or cover for the mouth of the bottle or jar.

Figure 1 is a side view of my newly designed bottle or jar. Fig. 2 is an edge view of the same. Fig. 3 is a view in perspective of the cap or cover.

A indicates the main body of the jar, which is oval or elliptical in form in cross-section and terminates at the neck in an annular rim or projection, B. The edges of the main body have a projecting rib or fin, C, which extends from the bottom of the jar up to the annular rim B.

D are beads or flutings on each side of the 30 rib or fin C, and form the ornamental portion of the jar. The neck of the jar extends up from the annular rim B.

H is the cap or cover having plain sides, the central portion of the top or upper side 35 being also plain, as shown at I.

K are beads or flutings arranged around the plain central portion of the cap, and form the ornamental portion of this part of the jar.

I claim as my invention—

1. The design for a bottle or jar, composed of the oval or elliptical body A, having the rims or fins ornamented with beads or flutings on the edges thereof, and the annular ledge or rim B, substantially as shown, and described. 45

2. In the design for a bottle or jar, the cap having plain sides, the central portion of the top plain, and a series of beads or flutes forming an annular band around said plain portion, substantially as described and shown. 50

In testimony whereof I affix my signature in presence of two witnesses.

THOMAS B. ATTERBURY.
